SHOE ATTACHMENT

Claude A. Cavey, Helen M. Copin, Aurora V. Hill, and Helen C. Hunt, Los Angeles, Calif.

Application May 6, 1939, Serial No. 272,228

1 Claim. (Cl. 36—7.5)

This invention relates generally to shoes and particularly to attachments for shoes.

It is a primary object of this invention to provide an inexpensive article for attachment to any ordinary shoe in order to provide a cushioned member between the shoe and a walking surface. The shoe attachment is particularly designed to make walking easy and less tiring for people who are wearing shoes which are not particularly adapted for extensive walking and in this connection the article is suitable for use by people attending expositions and the like where a great amount of walking is often done by people not wearing comfortable shoes for the occasion.

15 It is also an object of this invention to provide a shoe attachment which is a distinct "foot aid" to people who are on their feet a great deal of the time. It is also an object of this invention to provide an article which may be used by people 20 to deaden or quiet the sound of footsteps at places where noise cannot be tolerated, such as in broadcasting studios, motion picture sound stages and hospitals.

It is a particular object of this invention to 25 provide a shoe attachment which has a thick resilient cushion adapted to be positioned under the sole of a shoe and which is provided with a light weight upper extending upwardly from the thick sole and adapted to receive the forward 30 portion of a shoe.

It is also a particular object of this invention to provide a shoe attachment of the type indicated which is of light weight and may be rolled up into small compass so as to be easily 35 carried. It is a further object of this invention to provide an article of the type indicated which serves as a heat insulator between a shoe and a walking surface and thereby makes walking over hot surfaces much more comfortable than it 40 otherwise would be. It is also an object of this invention to provide an article of the type indicated which will protect the sole of a shoe from wear and abrasion caused by walking over uneven and rough surfaces.

45 These and other objects will be apparent from the drawing and the following description. Referring to the drawing, which is for illustrative purposes only;

Fig. 1 is a side elevation of the article of this 50 invention shown with relation to a woman's shoe; and

Fig. 2 is a sectional elevation on line 2—2 of Fig. 1.

Fig. 3 is a fragmentary section on line 3—3 55 of Fig. 1.

More particularly describing the invention, the shoe attachment has been indicated by reference numeral 11 and is shown in connection with a woman's shoe generally indicated by reference numeral 12. While the article of this invention has been shown in connection with a woman's shoe, it is contemplated that the article may be shaped so as to fit men's shoes and children's shoes and is not necessarily limited to application to women's shoes.

10 The shoe attachment comprises a relatively thick resilient sole member 13 which is preferably formed of a resilient sponge-like rubber although other resilient material might be used in place thereof. It has been found that a water-cured aerated latex sold under the name of "Airfoam" is particularly suitable for this purpose in that it is resistant to wear, is effective as heat insulation for the purposes desired, is resilient, and extremely light in weight. The sole member 15 is shaped to approximately correspond to the shape of the portion of the sole of the shoe which engages a walking surface during use. The front and rear edges of the member 13 are bevelled or 20 chamfered to a thin edge as indicated at 14 and 25 15 respectively.

Extending around the two side edges of the sole member 13 and around the front edge thereof is what will be termed an upper which has been generally indicated by reference numeral 16. 30 This upper may be formed of any suitable material, however, in order to provide an article of light weight and one which will be cool for the wearer, the upper has been shown as comprising a mesh or net material. The upper is attached at its lower margin by means of a strip of material or tape 17 which extends over the lower margin of the upper and around the two side edges and front edge of the sole member 13. Any suitable bonding material, such as rubber cement or the like, may be used between the tape 17 and the sole 13 in order to secure the upper to the sole. It is to be understood that some other means may be used for attaching the upper to the sole.

35 The upper when in position on a shoe 12 extends upwardly from the sole member 13 to engage the sides 12' of the shoe and to extend over the toe portion of the shoe. Thus, the sole member 13 and upper 16 cooperate to receive the forward portion of a shoe. The upper margin of the upper 16 is provided with a hollow or tubular tape 18 which forms a border for the upper, the tape being folded back upon itself and stitched at 19. A draw string 20 is provided which 40 45 50 55

tends through the tape 17 and is adapted to be extended rearwardly thereof a sufficient distance so that it may be secured around the heel of a shoe.

- 5 While the shoe attachment of this invention has been shown with a draw string 20 and a hollow tape 18, it is within the scope of this invention to provide some other border means for the upper 15 and to provide a suitable member 10 extending rearwardly thereof for attachment around the heel of a shoe such as a resilient band or the like.

Although the invention has been particularly shown and described, it is contemplated that certain changes may be made without departing from the scope of the invention and it is intended to cover such changes as come within the scope of the claim.

We claim as our invention:

- 20 A shoe attachment comprising a relatively thick resilient sole member having bevelled front and rear edges formed of a sponge-like rubber mate-

rial, said sole member being shaped to approximately correspond to the shape of the portion of the sole of a shoe which engages a surface during use, an upper of flexible net material extending upwardly from the front and side edges of said sole member and forming a toe portion and side portions, the lower margin of said upper being positioned about the front and side edges of said sole member, a tape extending around the front and side edges of said sole member over 10 said lower margin of said upper, a bonding material between said tape and said sole member and between the meshes of the lower margin of said upper for securing said upper to said sole member, a hollow tape secured to the upper edge of 15 said upper, and a draw string in said hollow tape and extending therefrom for rearward extension about a shoe.
